DESIGN.

—o—
J. SLATER.

DISH.

No. 18,020.

Patented Jan. 17, 1888.

UNITED STATES PATENT OFFICE.

JOHN SLATER, OF BURSLEM, ENGLAND.

DESIGN FOR A DISH.

SPECIFICATION forming part of Design No. 18,020, dated January 17, 1888.

Application filed November 29, 1887. Serial No. 256,486. Term of patent 3½ years

To all whom it may concern:

Be it known that I, JOHN SLATER, a subject of the Queen of England, residing at Burslem, England, have invented a certain new and original Design for Dishes, fully described and represented in the following specification and the accompanying illustration, forming a part of the same.

This invention relates to a design for the configuration and ornamentation of the deep dishes of a table service.

One feature of the design consists in the body of the dish, the same having substantially vertical sides, which are curved or bent inward at a point about one-half the height of the dish and swell out in a graceful curve both above and below this central depression.

Another feature of the design consists in having the lower portion or section of the body ornamented by a series of oblique corrugations of ogee form, which form a zone or band extending around that part of the dish.

As a full understanding of the design can best be given by an illustration of a dish embodying the same, such illustration is herewith given, such illustration showing an ordinary covered deep dish embodying the design.

Referring to said illustration, it will be seen that the dish therein shown is provided with

substantially vertical sides, which are bent or curved inward at a point about one-half their height, as indicated at *a*, thus providing a central depression extending entirely around the body of the dish. Above and below this depression *a* the sides of the dish swell outward in graceful curves *c*, thus giving a pleasing configuration to the dish. The lower part or section of the dish below the depression *a* is ornamented by a series of oblique corrugations, *d*, which are of ogee form, and form a band or zone extending entirely around that portion of the dish.

What is claimed is—

A design for the configuration and ornamentation of a dish, consisting of the substantially vertical sides curved or bent inward at about the middle of their height and swelling outward above and below said depression, the part of the sides below said depression being provided with oblique corrugations of ogee form, substantially as shown and described.

In testimony whereof I have hereunto set my hand in the presence of two subscribing witnesses.

JNO. SLATER.
